LAND LEVELING MACHINE

Berton M. Mathias, Monte Vista, Colo.

Application April 29, 1949, Serial No. 90,470

3 Claims. (Cl. 37—126)

1

This invention relates to land leveling machines, and more particularly to a large, power-operated machine for leveling agricultural lands for irrigation, aircraft runways, and other large areas where a level condition of the surface is desired.

It is among the objects of the invention to provide an improved land-leveling machine having a movable scoop for either storing or dumping earth, depending upon the position of the scoop, and power-operated means automatically controlling movements of the scoop in accordance with the level of the land below the scoop, so that the machine will remove earth from high places in the area and deposit it in low places in proportion to the departure of such low places from the general level desired, which machine has a length sufficient to obtain a level condition of the area regardless of small or local rises and depressions, and includes means for leveling minor irregularities in the path of the machine-supporting wheels and for removing obstructions, such as stones and debris, from the path of such wheels, which further includes means for supporting its front end over an elongated contact area with the ground surface, so that minor irregularities in the untreated ground ahead of the machine will not cause the machine to deviate materially from the general level desired, and which machine is simple, strong and durable in construction, economical to manufacture, easy to use and to transport from place-to-place, and substantially fully automatic in operation.

Other objects and advantages will become apparent from a consideration of the following description and the appended claims in conjunction with the accompanying drawings, wherein:

Figure 1 is a top plan view of a land-leveling machine illustrative of the invention, certain portions being broken away and omitted for the purpose of simplifying the drawings;

Figure 2 is a side elevation of the land-leveling machine illustrated in Figure 1;

Figure 3 is a longitudinal, medial cross-section on an enlarged scale of a hydraulic mechanism constituting an operative component of the machine illustrated in Figures 1 and 2;

Figure 4 is a perspective view of a fragmentary portion of the machine showing certain details of construction thereof; and

Figure 5 is a transverse cross-section on the line 5—5 of Figure 2.

With continued reference to the drawings, and particularly to Figures 1 and 2, the machine comprises, in general, an elongated structural frame

2

10, a pair of rear wheels 11 secured to and supporting the rear end of the frame, a pair of front wheels 12 secured to and supporting the front end of the frame, a machine-towing tongue 13 for operatively connecting the machine to a towing tractor, steering mechanism 14 operatively interconnected between the tongue 13 and the steerable front wheels 12, a pair of skids 15 carried by the frame below the latter and respectively in advance of the front wheels 12, a pair of scrapers 16 disposed below and carried by the frame at the front end of the latter and positioned respectively in advance of the skids 15, a scraping blade 17 extending transversely below the frame substantially at the mid-length location of the latter, a scoop 18 pivotally connected at its forward edge to the frame at the upper, rearward edge of the blade 17, a hydraulic mechanism 19 operatively inter-connected between the frame 10 and the scoop 18 for tilting the scoop, and a ground-engaging wheel 20 pivotally carried by the frame 10 adjacent the blade 17 and operatively connected to the hydraulic mechanism 19 to control the tilting of the scoop 18 by the hydraulic mechanism in accordance with the departure of ground depressions from the general ground level desired.

The frame 10 may be conveniently provided as an elongated, trussed structure of suitable structural iron shapes, such as angle irons, channel irons, and I-beams, and is of the lightest weight possible consistent with the necessary high degree of longitudinal rigidity thereof. As illustrated, the frame comprises a substantially three-dimensional, rectangular, center portion 21, a tapering front portion 22 extending forwardly from the front end of the center portion, and a tapering rear portion 23 extending rearwardly from the rear end of the center portion.

Each of the rear wheels 11 is journaled in a respective fork 24, and each fork is provided with a respective, vertically-disposed stem 25 rotatably and slidably received in a respective, vertically-disposed sleeve 26 rigidly secured to the rear end of the tractor frame 10. A transverse shaft 27 is rotatably supported on the tractor frame adjacent the rear end of the latter, and this shaft has arms 28 extending rearwardly from the opposite ends thereof to locations adjacent the inner sides of the respective sleeves 26. Each sleeve 26 is provided with a longitudinally-extending slot 29, and each stem 25 is provided with a respective pin which projects outwardly through the slot in the respective sleeve 26 and into a slot in the outer end of the corresponding arm 28, so that the sleeves 26 will be raised or lowered relative to the

rear wheels 11 upon rotation of the shaft 27. The shaft 27 may be rotated by any suitable power or manually-operated means, a hand lever 30 being illustrated as secured at one end to the shaft 27 and cooperating with a toothed quadrant 31 to hold the rear end of the frame at any desired position of elevation relative to the rear wheels 11. This frame-elevating means is used primarily to raise the frame to a sufficient height relative to the rear wheels for transportation of the machine from place-to-place along highways and roads.

The stems 25 may be held against rotation relative to the sleeves by the outwardly-projecting pins, so that the rear wheels always extend directly rearwardly of the frame, or, if desired, suitable steering mechanism may be operatively connected between the frame and the rear wheels 11, so that the rear wheels can be steered to facilitate movement of the machine. Such steerable rear wheels would constitute a decided advantage since these machines are frequently sixty feet or more in length and difficulty would otherwise be encountered in moving them around sharp curves and intersections.

The front wheels 12 are journaled on individual struts 32 at the lower ends of such struts and these struts extend upwardly into respective frame-carried guides 33 and are slidable and rotatable in the guides. Respective steering arms 34 extend forwardly from the struts 32, and these steering arms are inter-connected at their forward, distal ends by a tie rod 35. A hinged steering arm 36 is pivotally mounted intermediate its length on a transverse frame member 37 by a pivot joint 38 disposed substantially at the mid-length location of the frame member 37. At its rearward end the arm 36 is provided with a longitudinally-extending slot, and a pivot pin 39 extends through this slot and is attached to the tie rod 35 substantially at the mid-length location of the latter. The tongue 13 is pivotally connected intermediate its length to the front end of the frame by a pivot joint 40, and its rearward end is pivotally connected to the forward end of the steering arm 36 by a link 41. With this construction, when the tongue 13 is swung from side-to-side by the towing tractor, the front wheels 12 will be correspondingly steered so that the front end of the land-leveling machine will track after the tractor.

A transverse shaft 42 is journaled in the frame 10 adjacent the guides 33, and arms 43 extend rearwardly from this shaft to the outer sides of the guides 33. Respective pins extend outwardly from the struts 32 and are engaged in respective slots provided in the rearward or distal ends of the arms 43, so that the front end of the frame 10 will be raised or lowered upon rotation of the shaft 42.

Any suitable manually, or power-operated means may be provided for imparting rotational movements to the shaft 42, but as illustrated, this means comprises an elongated hand lever 44 secured at one end to the shaft 42 and cooperating with a fixed, toothed quadrant 45 to hold the front end of the frame at any desired position of elevation relative to the front wheels 12.

A pair of elongated skids or runners 15 is positioned below the frame adjacent the front end of the latter and respectively in advance of the front wheels 12 and are rigidly secured to the frame by suitable means, such as the respective standards 47. When the frame is lowered to operative position, these skids rest upon the surface of the ground and, having in contact with

the ground a length which is a substantial fraction of the total length of the machine, tend to level out minor inequalities in the ground surface, so that, when the machine is in operation the bottom of the frame does not deviate substantially from the general level desired.

The skids are preferably adjustable in a vertical direction relative to the frame, and this is accomplished by extending the respective standards 47 through corresponding apertured lugs 48 secured to the frame at the front end of the latter and adjustably securing the standards in the lugs by suitable means, such as the set screws 49.

The scrapers 16 are positioned respectively in advance of the skids 15, and are supported in advance of the frame 10 by respective brackets 50 which project forwardly from the frame and are provided at their forward ends with eyes 51 which slidably receive the scraper standards 52, these standards being held in adjusted position in the adjusted eyes 51 by suitable means, such as the set screws 53.

It will be noted that the hinged joint 54 in the steering arm 36 permits the frame to be raised and lowered relative to the front wheels 12 without disrupting the steering mechanism.

The scraper blade 17 extends transversely of the frame 10 at the bottom of the frame and substantially at the mid-length location of the frame, and is rigidly secured to the frame by suitable means, such as by being welded, as indicated at 55, at its ends to the respective bottom, longitudinal members 56 of the frame, as clearly illustrated in Figure 4. This blade extends downwardly and forwardly to a location somewhat below the frame and is beveled on its bottom edge, as indicated at 57, to provide a cutting edge 58. At its upper, rearward end the blade is provided with a series of spaced-apart, cylindrical eyes 59 which receive a rod 60 which extends transversely of the frame and serves as a hinge pin for the scoop 18. A reinforcing web 61 extends from the rear side of the blade near the lower end of the latter to the lower sides of the cylindrical eyes 59, and is welded along its opposite edges to the blade and to the eyes to provide a strong and rigid construction for the blade.

When the machine is pulled across the area to be leveled with the frame in proper lowered position relative to the rear and front wheels, and with the skids 15 resting on the ground, the cutting edge of the blade 17 will shear off all of the high portions of the ground down to the prescribed level, and the earth thus sheared off by the blade 17 is moved rearwardly into the scoop 18 by the forward movement of the machine.

The scoop 18 is a box-like structure having an open top and front end, and is pivotally connected at its forward edge to the frame at the upper, rearward edge of the blade 17 by spaced-apart, cylindrical eyes 62 which surround the rod 60 and constitute a piano-type hinge joint for the front edge of the scoop. The scoop 18 has a width substantially equal to the width of the frame 10 and to the length of the blade 17, and when this scoop is in its fully lowered position, as illustrated in Figure 2, its bottom 63 rests upon the bottom members of the center portion 21 of the frame as indicated at 63', and is disposed in a substantially horizontal position. This scoop is tiltable about the hinge joint provided by the eyes 62 and the rod 60 by raising its

rearward end to incline its bottom 63 forwardly and downwardly to spill or dump earth from the scoop over the blade 17 to the ground when low places in the ground are encountered, and this tilting of the scoop is accomplished by the hydraulic mechanism 19.

The hydraulic mechanism 19 comprises an elongated cylinder 64 which extends longitudinally of the center portion of the frame above and forwardly of the scoop 18, and is pivotally connected at its forward end to a transverse frame member 65 by a suitable pivotal connection including spaced-apart, apertured lugs 66 on the frame member, an apertured eye 67 on the end of the cylinder, and a pivot pin 68 extending through the lugs 66 and the eye 67. A piston 69 is reciprocable in the cylinder 64 and a piston rod 69 extends rearwardly from the piston 69 through a stuffing box 70 in the rear end of the cylinder and is pivotally connected at its rearward end to the rear end of the scoop 18. This pivotal connection may conveniently comprise a pair of spaced-apart, apertured lugs 71 upstanding from the scoop at the rear end of the latter, an apertured eye formed on the rear end of the piston rod 69, and a pivot pin 72 extending through the lugs 71 and the eye on the rear end of the piston rod.

With this construction, when the piston 69 is moved forwardly in the cylinder 64, the rear end of the scoop 18 will be moved upwardly and forwardly, tilting the scoop bottom 63 to a forwardly and downwardly-inclined position for dumping earth from the scoop, and when the piston moves rearwardly in the cylinder the scoop will be returned to its earth-storing position, in which its bottom is substantially horizontal and rests upon the bottom members of the frame.

Movements of the piston 69 in the cylinder 64 are controlled by a hydraulic valve, generally indicated at 73, and which is preferably mounted on the upper side of the cylinder 64.

The valve 73 has an outer shell or housing 74, preferably of elongated, cylindrical construction which is fixed relative to the movable parts of the valve and is preferably rigidly mounted on the hydraulic cylinder 64. A tubular plunger 75 is slideable in the housing 74, and an inner plunger 76 is longitudinally slideable in the tubular plunger 75 and the housing 74. The housing 74 is provided, substantially at its mid-length location, with a pressure fluid inlet port 77 from which a fluid conduit 78 extends to a suitable source of hydraulic fluid under pressure, such as the hydraulic pump outlet of the machine-towing tractor. At opposite sides of the inlet port 77, the housing is provided with respective outlet ports 79 and 80 which are substantially equally spaced from the inlet port 77, and from which respective conduits 79' and 80' extend to a suitable fluid sump connected with the inlet of the hydraulic pump of the tractor. Preferably the conduits 79' and 80' are Y-ed together, to provide a single return line extending forwardly of the machine frame 19 for connection to the tractor hydraulic pump sump.

The tubular valve plunger 75 has thereon external, annular valve gates 82, 83, 84, 85, 86 and 87 spaced apart longitudinally on said plunger to provide annular reduced portions between adjacent gates. The two gates 82 and 87 are disposed at respectively opposite sides of the plunger, while the two gates 84 and 85 are disposed at respectively opposite sides of the inlet port 77 in the valve housing. The gate 83 is spaced

from the side of the outlet port 80 opposite the inlet port 77, and the gate 86 is correspondingly spaced from the outer side of the outlet port 79. A port 88 in the tubular plunger 75, between the gates 84 and 85, connects the inlet port 77 with the interior of the tubular plunger, and ports 89 and 90 between the gates 83 and 84, and the gates 85 and 86 respectively connect the outlet ports 80 and 79 with the interior of the tubular plunger 75. A port 91 opens to the interior of the tubular plunger 75 at a location adjacent the annular valve gate 84 and is connected by a longitudinally-extending passage 92 in the tubular plunger to a port 93 which opens to the exterior of the tubular plunger between the valve gates 82 and 83. Similarly, a port 94 opens to the interior of the tubular plunger 75 adjacent the valve gate 85 and is connected by a longitudinally-extending passage 95 to a port 96 which opens to the exterior of the tubular plunger between the valve gates 86 and 87.

A port 97 in the wall of the cylinder 64 opens to the exterior of the cylinder wall between the valve gates 82 and 83, and is connected by a passage 98 extending longitudinally through the wall of the cylinder to a port 99 which opens to the interior of the cylinder 64 at the rear end of the latter. Similarly, a port 100 opens to the exterior of the cylinder 64 between the valve gates 86 and 87, and is connected by a longitudinally-extending passage 101 to a port 102 which opens to the interior of the cylinder 64 at the front end of the cylinder.

The inner plunger 76 has three spaced-apart, valve gates or pistons 103, 104 and 105 thereon, and when the valve is in its neutral position, as illustrated in Figure 3, these three pistons respectively underlie the ports 89, 83 and 90 in the tubular plunger 75. A reduced portion 106 of the inner plunger 76 extends through a stuffing box 107 in the front end of the tubular plunger 75 and through the front wall of the housing 74 into the cylinder 108 of a hydraulic servo mechanism, the cylinder 108 being attached at its rear end to the front wall of the valve housing 74 by suitable means, such as the threaded connection 109. A piston 110 is secured on the end of the reduced portion 106 of the valve plunger 76 within the servo cylinder 108, and a hydraulic conduit 111 leads from the front end of the cylinder 108 to a hydraulic master cylinder 112 mounted on a vertical member of the machine frame 19. The master cylinder 112 may be a conventional master cylinder, such as is used in hydraulic brake mechanisms of automotive vehicles, and, since such master cylinders are well known to the art, a detailed description of the unit 112 is considered unnecessary for the purposes of the present disclosure.

A ground-engaging wheel 20 is journaled in the outer end of a fork 113 provided on one leg 114 of a bell crank lever, generally indicated at 115, which is pivotally mounted at its knee on the frame by a pivotal connection 116 secured to a vertical frame member, preferably the member on which the master cylinder 112 is mounted. The other or vertically-disposed leg 117 of the bell crank lever is connected at its upper end to the plunger 118 of the master cylinder 112, the arrangement being such that when the wheel 20 drops into a depression in the ground, the plunger 118 is pulled outwardly of the master cylinder 112 and when the wheel 20 is raised by a succeeding high portion in the ground the plunger 118 is forced inwardly of the master cylinder.

Since the master cylinder 112 is connected to the servo cylinder 108 by the hydraulic conduit 111, movements of the plunger 118 will be transmitted to the piston 110 on the end of the inner valve plunger 76.

With this construction, when the wheel 20 descends into a low portion of the ground, the plunger 118 will be pulled out, withdrawing fluid from the cylinder 108 ahead of the piston 110 and permitting the compression spring 119 to move the inner plunger 76 forwardly. When this happens, the piston 104 uncovers the port 88 and connects it with the port 91 between the piston 104 and the piston 103, so that hydraulic fluid under pressure may flow from the conduit 78 through the ports 77, 88, and 91, the passage 92, the ports 93 and 91, the passage 93 and the port 99 into the rear end portion of the hydraulic cylinder 64 to force the piston 68 forwardly and raise the rear portion of the scoop 18.

As the rear portion of the scoop 18 is raised, the rear end of the hydraulic cylinder 19 will be correspondingly raised. An L-shaped bracket 120 projects upwardly and rearwardly from the rear end of the outer valve housing 74, and a bell crank lever 121 is pivotally mounted at its knee on the bracket 120 at the rear end of the latter. A link 122 connects the outer end of one leg of the bell crank lever 121 to the top of the frame 10, and the other leg of the bell crank lever is connected at its outer end to an actuating rod 123 which extends rearwardly on the rear end of the tubular valve plunger 75 through a stuffing box 124, in the rear end of the valve housing 74. The downwardly extending leg of the bell crank lever is provided with a longitudinally-extending slot 125, and a pin 126 secured to the rear end of the actuating rod 123 extends through this slot to provide a lost-motion connection between the bell crank lever and the rear end of the actuating rod.

With this construction, when the scoop is raised with the consequent raising of the rear end of the hydraulic cylinder 64, the tubular valve plunger 75 will be moved forwardly with the rising of the rear end of the scoop until the port 88 is again centered over the piston 104 of the inner plunger 76 of the valve, at which position of the scoop hydraulic fluid to the cylinder 64 will be cut off and the piston 68 stopped. Simultaneously the ports 89 and 90 are moved over the pistons 103 and 105, so that the return of hydraulic fluid from the hydraulic cylinder is also cut off and the scoop is held against movement in a predetermined position corresponding to the extent to which the ground-engaging wheel 20 has descended.

As long as the ground-engaging wheel continues to descend, the plunger 76 will be continuously moved forwardly and the tubular plunger 75 will continue to follow up this forward movement of the inner plunger as the scoop is tilted by the forward movement of the piston 68 in the hydraulic cylinder 64. Forward movement of the inner plunger 76 relative to the tubular plunger 75 also moves the piston 105 forwardly of the port 90, so that the forward end of the hydraulic cylinder 64 is connected to the return line 81 through the port 102, the passage 101, the ports 100, 96, the passage 95, the port 94, and the ports 90 and 79.

When the ground-engaging wheel rises and the plunger 118 is forced inwardly of the master cylinder 112, hydraulic fluid is forced into the servo cylinder 108, moving the piston 110 and

the inner valve plunger 76 rearwardly, reversing the above operation in a manner such that the front end of the hydraulic cylinder is connected with the fluid pressure conduit 78 and the rear end of the hydraulic cylinder is connected with the return conduit 82, so that the piston 68 will move rearwardly in the hydraulic cylinder to lower the scoop. Lowering of the scoop causes the tubular plunger 75 to also move rearwardly following the rearward movement of the inner plunger 76, so that the scoop will be lowered in proportion to the amount of rise of the ground-engaging wheel, and will be stopped whenever vertical movement of the ground-engaging wheel ceases.

With the above-described arrangement, the scoop will be tilted proportionately to the depth of any depression encountered by the ground-engaging wheel to dump into such depression the required amount of earth, which earth will then be leveled by the blade 17. If a deep depression is encountered, the scoop will be sharply tilted to quickly dump a large quantity of earth into the depression, whereas, if only a shallow depression is encountered, the scoop will be moderately inclined to dump a proportionately smaller quantity of earth into the shallow depression.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A land-leveling machine comprising an elongated frame having a front end and a rear end, wheels connected to said frame at its front and rear ends for supporting the latter, a scraper blade secured to and extending transversely of said frame near the mid-length location of the latter, said blade being inclined forwardly and downwardly relative to said frame, an earth-receiving scoop pivotally connected at its forward edge to said frame at the rear edge of said blade and extending rearwardly from the latter, hydraulic mechanism connected between said frame and said scoop for tilting said scoop about the pivotal connection between said scoop and said frame to discharge earth from said scoop, said hydraulic mechanism being movable relative to said frame and including a control valve, a bell crank lever pivotally mounted on said frame, a ground-engaging wheel carried by said bell crank lever at one end of the latter, a motion transmitting connection between the opposite end of said bell crank lever and said control valve, and a motion transmitting connection between said frame and said control valve for controlling the operation of said hydraulic mechanism to move said scoop in accordance with the vertical movements of said ground-engaging wheel.

2. A land-leveling machine comprising an elongated frame having a front end and a rear end, wheels connected to said frame at its front and rear ends for supporting the frame, a scraper blade secured to and extending transversely across said frame near the mid-length location of the latter, said blade being inclined forwardly and downwardly relative to said

frame, an earth-receiving scoop pivotally connected at its forward edge to said frame at the rear edge of said blade and extending rearwardly from the latter, power operated mechanism connected between said frame and said scoop for tilting said scoop about its pivotal connection with said frame to discharge earth from said scoop, control means connected to said power operated means, a lever pivotally connected to said frame and extending forwardly of said blade, a ground-engaging device carried by said lever ahead of said blade, motion transmitting means connected between said lever and said control means and motion transmitting means connected to said control means and responsive to movements of said scoop, said motion transmitting means together controlling the operation of said power operated means to tilt said scoop in accordance with the vertical movements of said ground-engaging device.

3. A land leveling machine comprising an elongated frame, a pair of rear wheels secured to said frame at the rear end thereof, a pair of steerable front wheels secured to said frame at the front end thereof, a scraper blade secured to and extending transversely of said frame near the midlength location of the latter, said blade being inclined forwardly and downwardly relative to said frame, an earth-receiving scoop pivotally connected at its front edge to said frame at the upper, rear edge of said blade and extending rearwardly from the latter, a vertically disposed bell crank lever pivotally mounted intermediate its length on said frame ahead of said blade, a ground-engaging wheel journaled on the lower end of said bell crank lever, a hydraulic expandible chamber device pivotally connected at one end to said frame and at its other end to

said scoop for tilting the latter, means connected to said expandible chamber device for supplying hydraulic fluid under pressure thereto, a control valve connected to said expandible chamber device for controlling the admission of hydraulic fluid under pressure thereto and including an outer part and two cooperating inner parts movable relative to each other end to said outer part to provide a follow-up control between said ground-engaging wheels and said scoop, motion transmitting means connected between the upper end of said bell crank lever and one of the inner parts of said control valve, and motion transmitting mechanism connected to the other inner part of said control valve and responsive to tilting movements of said scoop.
